UNITED STATES PATENT OFFICE.

RENA W. THAYER, OF SPRINGFIELD, MASSACHUSETTS.

ATTACHMENT FOR BARRETTES.

1,343,239.

Specification of Letters Patent. Patented June 15, 1920.

Application filed June 5, 1919. Serial No. 302,014.

To all whom it may concern:

Be it known that I, RENA WALKER THAYER, a citizen of the United States, residing at Springfield, in the county of 5 Hampden and State of Massachusetts, have invented certain new and useful Improvements in Attachments for Barrettes, of which the following is a specification.

This invention relates to barrettes, and 10 more particularly to attachments therefor for securely holding up what are known as "scolding locks".

The object of the invention is to provide a detachable attachment of this character on 15 which the locks to be secured may be wound and the tongue of the barrette then connected with the attachment and passed through the hair and secured.

Another object is to so construct such an 20 attachment that it will prevent all possibility of the locks wrapped thereon from becoming loosened.

With the foregoing and other objects, in 25 view, which will appear as the description proceeds, the invention resides in the combination and arrangement of parts and in the details of construction hereinafter described and claimed, it being understood that changes in the precise embodiment of the 30 invention herein disclosed may be made within the scope of what is claimed without departing from the spirit of the invention.

In the accompanying drawings:—

Figure 1 represents a rear elevation of a 35 barrette equipped with this attachment,

Fig. 2 is a side elevation thereof,

Fig. 3 is a rear elevation of the attachment 40 detached, and

Fig. 4 is a similar view showing another form of the attachment applied, the barrettes being shown in dotted lines.

In the embodiment illustrated, a barrette 1 of ordinary construction is shown having the usual tongue 2 and catch 3 for securing 45 it. This tongue is in the form of a flat strip twisted at its pivoted inner end as shown at 4 so that the body portion thereof will be arranged parallel with the body of the barrette when in operative position.

50 The attachment shown in Figs. 1 to 3, which constitutes this invention is shown in

the form of a strip 5 having its ends 6 bent at an obtuse angle and apertured as shown at 7 for the passage therethrough of the tongue 2 when in use. 55

In the use of this attachment, the locks to be secured by the barrette are wrapped around the bar 5 and then the tongue 2 is passed through the ends 6 of said bar with the wrapped bar positioned between the 60 tongue and the barrette. The barrette is then engaged with the hair in the usual manner and the tongue secured by the catch 3.

In the form shown in Fig. 4, the attachment 5^a is constructed from a piece of wire, 65 the ends of which are welded or otherwise secured together so as to present no obstructions which would be likely to entangle in the hair. This wire loop is then twisted as shown at 8, with loops 9 at its opposite ends 70 which are bent to provide for the ready passage therethrough of the tongue 2 of the barrette. The twisted portion 8 of this wire is designed to prevent the locks wound thereon from slipping. 75

From the above description it will be obvious that this attachment may be constructed as an article of manufacture and sold at a very low cost for use in connection with any type of barrette having a tongue for 80 passage therethrough and that it will operate to effectively hold loose locks of hair up off the wearer's neck.

From the foregoing description, taken in connection with the accompanying drawings, the advantages of the construction and of the method of operation will be readily apparent to those skilled in the art to which the invention appertains and while I have described the principle of operation of the 90 invention together with the device which I now consider to be the best embodiment thereof, I desire to have it understood that the device shown is merely illustrative and that such changes may be made as are within the scope of the claimed invention. 95

Having thus fully described my invention what I claim as new and desire to secure by Letters Patent, is:—

1. The combination with a barrette having a tongue; of a lock securing attachment carried by the tongue and comprising an 100

elongated member having laterally offset obliquely disposed facewise extending apertured ends for the reception of the tongue.

2. The combination with a barrette having a tongue; of an attachment comprising a narrow elongated strip having openings in its opposite ends, said ends being bent at an obtuse angle facewise of the strip said ends extending in the same direction to facilitate 10 the passage therethrough of the barrette

tongue and to position the body portion of the strip in laterally spaced relation to the tongue.

In testimony whereof I affix my signature in presence of two witnesses.

RENA W. THAYER.
